COMBINED BLOWER AND SUCTION DEVICE

Filed Oct. 7, 1929

INVENTOR
Adam A. Brewer.

Charles D. Hill,
ATTY

UNITED STATES PATENT OFFICE

ADAM A. BREUER, OF CHICAGO, ILLINOIS

COMBINED BLOWER AND SUCTION DEVICE

Original application filed June 16, 1927, Serial No. 199,193. Divided and this application filed October 7, 1929. Serial No. 397,909.

This invention relates to a combined blower and suction device, and particularly to a novel handle for such device, which handle serves several useful purposes in connection 5 with the operation of the device.

Another object of the invention is to provide a handle for such a device or apparatus so arranged that its gripping portion is parallel to the axis of the discharge nozzle and 10 placed over the heavier part of the device in order to more easily balance the device when in use.

Above, other and further objects of the invention will be apparent from the following 15 description, accompanying drawings and appended claims.

This application is a division of co-pending application, Serial No. 199,193, filed June 16, 1927.

20 An embodiment of the invention is illustrated in the accompanying drawings, and the views thereof are as follows:

Figure 1 is a fragmental top plan view of the illustrated embodiment of the invention, 25 showing the same arranged as a suction cleaner.

Figure 2 is a side elevational view of the device arranged as a blower.

Figure 3 is an end elevation of the illustration of Figure 1, with certain parts removed and with the apparatus tilted at an angle.

The invention is illustrated in connection with a combined blower and suction apparatus or device which includes a fan casing 35 1 having an axial air inlet port 2 and a tangential air discharge port 3.

A motor casing 4 is secured to the fan casing 1 on the side opposite the air inlet port 2. The motor casing is secured by means of 40 bolts or screws 5, or like attaching means.

The air inlet port 2 may have connected to it by any suitable connection a suction hose 6, at the free end of which is provided a suction nozzle, while the air discharge port 45 3 may have connected to it a dirt bag 7 for collecting the dirt received through the suction hose 6, or, if the device is to be used as a blower, then an air discharge nozzle 8, preferably tapering toward the free end thereof, 50 is provided at the discharge port 3.

A screen 9 may be interposed over the air inlet port 2 for purposes well understood.

Preferably, the fan casing 1 and the motor casing 4 are made of aluminum, so that the apparatus will be light and readily usable. 55

The suction hose 6 may be secured to the air inlet port 2 by a bayonet joint or any other suitable manner, while the dirt bag 7 or the nozzle 8 may be secured to the air discharge port 3 in like manner. 60

This device is susceptible of selective use as a blower or as a suction cleaner.

A handle, including a gripping portion 10 and end legs 11 and 12, is secured to or cast integrally with the motor casing 4. The illustrated form of the invention shows the handle attached to the motor casing by means of screws 13 passing through apertured lugs 14 of the handle. The middle of the handle is preferably placed over the axis of the 70 motor.

The gripping portion 10 is made hollow to accommodate a snap switch operable outwardly of the handle by means of a lever 15 for controlling the motor circuit. Said 75 lever 15 projects through a slot 16 in the handle.

One of the legs 12 of the handle is provided with a slot 17 which slot extends lengthwise of the leg for the reception of a strap 18 passing through said slot and which serves to support the weight of the device from the shoulders of the operator, thus leaving the gripping portion 10 of the handle 3 for manipulation of the device. 85

The gripping portion 10 of the handle is parallel to the tangential nozzle 8, which arrangement enables easy manipulation of the apparatus and, at the same time, balances the weight of the same about the axis of the motor. 90

Figure 1 illustrates a device when arranged as a vacuum cleaner with the suction hose 6 connected to the air inlet port 2 and a dirt bag 7 connected to the air discharge port 3. 95 The screen 9 may be used when the device is used as a suction cleaner as well as a blower. However, it is preferable to eliminate the plate 9 when the apparatus is used as a suction cleaner. 100

Figure 2 illustrates the appearance of the machine when used as a blower with the nozzle 8 applied at the air discharge port 3. The nozzle is removably attached to the fan casing 1 by a bayonet joint or any other suitable connection.

The gripping portion 10 of the handle, being tangential to the blower nozzle 8, allows greater ease in the manipulation of the apparatus and also aids in directing the discharge nozzle more uniformly. Furthermore, it adds to the balance effect of the whole structure.

The perforated plate may be suitably arranged in the air intake port 2 for ready removal and insertion as desired.

The invention has been described herein more or less precisely as to details, yet it is not to be limited thereby, as changes may be made in the arrangement and proportion of parts and equivalents may be substituted without departing from the spirit and scope of the invention.

The invention is claimed as follows:

25 A portable convertible blower comprising in combination, a motor casing, a fan casing, said fan casing having an air inlet port and a tangentially arranged air outlet nozzle, a D-handle attached to the motor casing, said 30 handle consisting of a hollow gripping portion and two legs, said handle being attached to the motor casing with the grip portion thereof parallel to said tangentially disposed outlet, a switch in said hollow gripping portion, a switch-operating lever projecting from said grip portion ahead of the rear leg of said handle, said handle having a longitudinally extending strap slot in its rear leg and a strap in said slot for supporting the weight 35 of said device in use, said handle serving as means for directing the tangential outlet toward a work piece, the strap supporting the blower in use and enabling the utilization of the handle solely as means for manipulating 40 the device in use.

In testimony whereof I have hereunto subscribed my name at Chicago, Cook county, Illinois.

ADAM A. BREUER.
